UNITED STATES PATENT OFFICE

HARRY T. KINGSBURY, OF KEENE, NEW HAMPSHIRE, ASSIGNOR TO KINGSBURY MFG. COMPANY, OF KEENE, NEW HAMPSHIRE, A CORPORATION OF NEW HAMPSHIRE

DESIGN FOR A BATTERY FLASH LIGHT

Application filed March 18, 1933. Serial No. 47,523. Term of patent 14 years.

To all whom it may concern:

Be it known that I, HARRY T. KINGSBURY, a citizen of the United States, residing at Keene, county of Cheshire, and State of New Hampshire, have invented a new, original, and ornamental Design for a Battery Flash Light of which the following is the specification, reference being had to the accompanying drawing forming part thereof.

In the drawing:-

Figure 1 is a perspective view of the device, showing my new design; and

Fig. 2 is a side elevation of the same.

The distinctive feature of the present invention is the configuration of the lamp cap and base which are to be applied to a battery which is shown in broken lines in the drawing.

I claim

The ornamental design for a battery flash light, as shown and described.

In testimony whereof, I affix my signature.

HARRY T. KINGSBURY.
